UNITED STATES PATENT OFFICE

156,691

COMBINATION CHAIR AND COSTUMER

Edgar Belmont, Port Chester, N. Y.

Application March 12, 1947, Serial No. 137,541

Term of patent 14 years

(Cl. D15—1)

To all whom it may concern:

Be it known that I, Edgar Belmont, a citizen of the United States and a resident of Port Chester, county of Westchester, and State of New York, have invented a new, original, and ornamental Design for a Combination Chair and Costumer, of which the following is a specification, reference being had to the accompanying drawing, forming part thereof.

Figure 1 is a perspective view, from the front, of a combination chair and costumer, showing my new design;

Figure 2 is a similar view from the rear;

Figure 3 is a perspective view showing certain of the parts in an adjusted relationship; and

Figure 4 is an enlarged cross-sectional view taken substantially along the line 4—4 of Figure 2.

I claim:

The ornamental design for a combination chair and costumer, substantially as shown.

EDGAR BELMONT.
